UNITED STATES PATENT OFFICE.

JOHN WILSON BROWN, JR., OF PHILADELPHIA, PENNSYLVANIA, ASSIGNOR
TO THE ENTERPRISE MANUFACTURING COMPANY OF PENNSYLVANIA,
OF SAME PLACE.

DESIGN FOR A PUMP-HEAD.

SPECIFICATION forming part of Design No. 28,191, dated January 18, 1898.

Application filed August 25, 1897. Serial No. 649,537. Term of patent 14 years.

To all whom it may concern:

Be it known that I, JOHN WILSON BROWN, Jr., a citizen of the United States, residing in Philadelphia, Pennsylvania, have invented 5 a certain new and useful Design for a Pump-Head, of which the following is a specification.

My design for the head of a pump is clearly illustrated in the accompanying drawings, in 10 which—

Figure 1 is a plan view. Fig. 2 is a side view; and Fig. 3 is an end view looking in the direction of the arrow, Fig. 1.

The essential feature of the design is the 15 standard, having an enlargement at the top and an arm projecting from one side.

A is the standard, supporting an enlargement B, and projecting from the standard, below the enlargement, is an arm D.

I claim—

The design for the head of a pump, as herein described and as shown in the accompanying drawings.

In testimony whereof I have signed my name to this specification in the presence of 25 two subscribing witnesses.

JOHN WILSON BROWN, JR.

Witnesses:

WILL. A. BARR,
JOS. H. KLEIN.
